ADJUSTABLE SHELF SUPPORT

Enoch Swedman and Carl E. Norelius, St. Paul, Minn., assignors to Seeger Refrigerator Company, St. Paul, Minn., a corporation of Minnesota

Application February 10, 1939, Serial No. 255,627

7 Claims. (Cl. 211—92)

Our invention relates to an improvement in adjustable shelf supports wherein it is desired to provide a means of supporting a shelf so that the same may be tilted at various angles.

5 Numerous devices for the purpose of supporting shelves at one angle or another have previously been constructed. Many of these constructions disclose a brace which is adjustable in length to be attached to the outer end of a shelf which is pivoted at the back so as to raise or lower the front end of the shelf. The problem of making the brace adjustable in length, while not difficult, is usually somewhat costly, and the manner of adjustment is not particularly easy to accomplish.

10 Brackets have been provided so that a brace may be secured in various positions to the bracket so as to change the position of a pivoted shelf. In this type of construction, however, in order to provide the desired amount of adjustment, the bracket must be of considerable length.

It is a purpose of the present invention to provide a shelf support in which the shelf is supported upon one bracket arm while a brace is attached to the outer end of the shelf and is pivotal with relation thereto. Both of these bracket arms are adjustably engaged in a suitable bracket, and accordingly, the bracket is greatly reduced in size due to the fact that both of the supporting arms are adjustable. Furthermore, this construction enables the shelf to be entirely removed in a simple and easy manner.

It is a purpose of the present invention to provide a shelf support including a pair of bracket arms which are adjustably secured to a suitable bracket. In attaching the bracket arms to the bracket, the arms are bent to extend through apertures in the bracket. These bent ends are of such a shape that the ends may be easily removed from the apertures when this is desired but are shaped in such a way that they cannot readily be accidentally disengaged from the bracket.

It is a purpose of our invention to provide a construction whereby a plurality of shelves may be secured in alignment to brackets so that the individual shelves may be individually adjusted to accommodate the articles to be placed upon the same. In this way one shelf may be tilted to display the tops of packages placed thereupon whereas vertical articles may be stood up on the other shelf and viewed from the front in elevation.

It is a further feature of our invention to provide a shelf support by means of which the shelf may be positioned nearer to or farther from the rear surface of the refrigerator or wall to which

the shelf is attached. With our construction the shelf may be moved forwardly or rearwardly by adjusting the supporting bracket arm and brace with respect to the bracket.

These and other objects and novel features of our invention will be more clearly and fully set forth in the following specification and claims.

In the drawing forming a part of our specification:

Figure 1 is a cross-sectional view through a refrigerator showing an end view of a shelf which is adjustably supported.

Figure 2 is a perspective view of one of the brackets and the supporting arms secured thereto which arms support the shelf.

Figure 3 is a plan view looking down upon the ends of two adjacent shelves which are attached to a single bracket.

Our adjustable shelf support A is particularly designed for use in a display refrigerator B or the like. This type of refrigerator ordinarily is provided with a solid top portion 10, front windows 11, through which the contents of the refrigerator may be viewed, and rear sliding doors or panels 12. The brackets A are preferably secured to the interior rear mullion and stiles by any suitable means such as heavy wood screws 13 indicated in Figure 1 of the drawing.

The brackets A comprise frustro-pyramidal brackets having side walls 14, a top wall 15, a front wall 16, and a rear wall 17. The rear wall 17 bears against the interior mullion or stile of the refrigerator and is secured thereto by means of the heavy wood screws 13 which extend through this rear wall 17. The bottom of the bracket A is preferably open in order that axis to the screws 13 may be readily obtained.

The top wall 15 of the bracket A includes a series of openings 19 which are provided in alignment between the front and rear walls of the bracket. Either one or both of the side walls 14 are provided with a series of openings 20 as illustrated in Figure 1 of the drawing to receive the shelf supporting brace.

The shelf C is of any desired formation and is shown in the drawing as comprising a pair of longitudinally extending base wires 21 to the upper surface of which transverse tray wires 22 are secured. The tray wires 22 preferably bend upwardly at each end at 23 and a longitudinally extending wire rail 24 connects each series of ends of the transverse tray wires 22.

A bracket arm 25 is connected to the longitudinally extending base wires 21, being secured to the ends of the inner-most base wire 21 and 55

being secured to the other wire 21 at a point 26 near the end of the same. This brace wire 25 is provided with a substantially S-shaped end 27 which is designed to extend through any of the apertures 19 in the top wall 15 of the bracket A. 5 The end 27 is so shaped that when the shelf is in position, the body of the wire overlies the portion of the upper wall 15 of the bracket between the aperture 19 through which the wire extends, 10 and the front of the bracket. The end 27 of the wire 25 extends downwardly through the opening 19 and is bent substantially parallel to the main portion of the wire 25 to provide an end portion which underlies the upper wall 15 of the bracket 15 A and which may therefore not be removed from the opening 19 without raising the bracket arm 25 into position at substantially right angles to the top wall 15 of the bracket.

A brace arm 29 is provided with a sleeve 30 which is secured at substantially right angles to 20 the arm 29 and which is designed to accommodate the end of the longitudinally extending base wire 21 beyond the connection point 26 of the same. This brace rod or wire 29 is provided with 25 end portions 31 which are bent at slightly less than 90° to the axis of the rod. These ends 31 are provided to extend through any of the openings 20 in the side walls 14 of the brackets A. As the ends 31 are not entirely right-angular, 30 with respect to the axis of the rod, a downward or inward pressure on the right tends to force the ends 31 more deeply into engagement with the openings 20.

If only a single C shelf is provided, the shelves 35 and brackets are formed in the manner which has been described. If more than a single shelf is to be provided in abutting relation, an intermediate bracket A' indicated in Figure 3 is provided. This bracket is designed to be held in 40 place by screws 13' and is provided with a rear wall 17', side walls 14', and a top wall 15'. Two rows of openings 19' arranged in parallel relationship are extended through the top 15' and both of the side walls 14' are provided with openings 20'. With this construction it is obvious 45 that two parallel bracket arms 25 can be secured in the top of the bracket A', as indicated in Figure 3 of the drawing and two brace arms 29 may be secured in the side walls 14' of the bracket 50 A'. Obviously either of the bracket arms 25 or the brace arms 29 can be independently adjusted so that the shelves may be tilted independently to any desired angle.

In operation, the shelves C are engaged in the 55 brackets A by holding the shelf C at almost right angles with respect to the top 15 or 15' of the brackets so that the ends 27 of the bracket arms 25 may be inserted through the row of openings in the top surface of the bracket. When the 60 bracket arms 25 have been secured in proper position in the bracket to place the shelf at the proper distance from the rear wall of the refrigerator, the brace arms 29 are either slipped over the extending ends of the base rods 21 and then 65 inserted into the openings 20 or 20' in the brackets, or else may be inserted in the bracket first and then engaged on the end of the rods 21.

It will be noted that by moving the bracket rod 25 rearwardly into the rear opening 19 in the 70 top of the brackets and by moving the rods 29 forwardly to engage the front openings in the brackets, the shelf may be tilted upwardly so that the front is substantially higher than the back of the shelf. However, if it is desired to tilt the 75 shelf C forwardly, the bracket arm 25 may be

engaged in one of the front openings 19 or 19', whereas the brace arms 29 are engaged in a rear opening 20 or 20'. The shelf C will then be supported in a forwardly tilted position so that articles lying flat upon the shelf may be readily displayed through the windows 11. It will be further noted that by moving both the arm 25 and the brace arm 29 forwardly and rearwardly in unison upon the brackets A, the shelf may be moved forwardly away from the doors 12 of the 10 refrigerator or may be moved rearwardly toward these doors.

In accordance with the patent statutes, we have described the principles of construction and operation of my adjustable shelf support; and 15 while we have endeavored to set forth the best embodiments thereof, we desire to have it understood that these are only illustrative of a means of carrying out our invention, and that obvious changes may be made within the scope of the following claims without departing from the spirit 20 of our invention.

We claim:

1. An adjustable shelf support comprising a bracket having a top wall and side walls and 25 having a series of openings through said top wall and through one of said side walls, a shelf having a bracket arm secured thereto engageable in any of said openings in said top wall, and a brace arm pivotally secured to said shelf and engageable 30 in any of said apertures in said side wall.

2. An adjustable shelf comprising a pair of spaced brackets having an upper surface and a side surface, said upper surface and said side surface having a series of openings therethrough, 35 a shelf having a bracket arm secured to each end thereof engageable in any of said openings in said top surface, and a brace arm pivotally secured to said shelf engageable in any of said openings in said side surface.

3. An adjustable shelf comprising a pair of spaced brackets, each including a pair of bracket surfaces arranged at substantially right angles, each of said bracket surfaces containing a series 45 of spaced openings, a shelf having a bracket arm engageable with the openings in one of said surfaces, and a brace arm pivotally secured to said shelf and engageable in any of the openings in the other of said surfaces.

4. A refrigerator shelf construction comprising 50 a bracket having a pair of surfaces arranged at substantially right angles and having openings therethrough, a shelf having a bracket arm secured to one end thereof, said bracket arm engageable in the openings in any of said surfaces, 55 a brace arm pivotally secured to said shelf, and means on said brace arm engageable in any of the openings of the other of said surfaces.

5. An adjustable shelf comprising a pair of spaced brackets, each of said brackets having a 60 pair of surfaces thereupon extending at substantially right angles, each of said surfaces having a series of openings therethrough, a shelf having a bracket arm secured to each end thereof, a substantially S-shaped end on each of said 65 bracket arms engageable in any of the openings in one of said surfaces, a brace arm pivotally secured to said shelf, and a bent end on said brace arm engageable in any of the openings of the other of said surfaces.

6. An adjustable shelf comprising a pair of spaced brackets, each bracket of which includes 70 a pair of surfaces arranged on planes at substantially right angles, each of said surfaces having a series of openings therethrough, a shelf, a 75

- bracket arm on each end of said shelf and extending beyond the shelf, a substantially S-shaped end on said extended portion of said bracket arm engageable in any of the openings of 5 one of said series, a brace arm pivotally secured to said shelf, and an end on said brace arm bent at slightly less than 90° to the axis of said brace arm and engageable in any of said openings in the other of said surfaces.
10. 7. An adjustable shelf comprising a pair of spaced brackets, an intermediate bracket between said spaced brackets, a shelf extending between each of said spaced brackets and said intermediate bracket, each of said brackets hav-
- ing two surfaces arranged at substantially right angles, each of said surfaces having a series of openings therethrough, the surfaces of said intermediate bracket having two series of apertures on each surface thereof, a bracket arm on each end of each shelf, an end on each bracket arm engageable with any of the series of openings on one surface of said brackets, and a brace arm pivotally secured to each end of said shelf and engageable in the openings in the other surface 10 of said brackets. 5
